INDEX PANEL WITH ADJUSTABLE STOP

Lloyd M. Toms, Crozet, Va., assignor to Acme Visible Records, Inc., Chicago, Ill., a corporation of Delaware

Application October 16, 1952, Serial No. 315,121

2 Claims. (Cl. 129—16)

This invention relates to card index panels of the type used in books, filing cabinet drawers and the like for the filing of index cards in visible, alphabetical or other order, and is more particularly concerned with card index panels having card carrier elements on which the index cards are slidably, removably supported against a stop member adjustably positioned along the guide elements to facilitate rearrangement of the cards or expansion or contraction of the card index system.

This invention further contemplates the provision of an index panel having a guide element including spaced parallel flanges slidably engaging spaced cut out tongues formed on index cards arranged in overlapping relation along the guide element, the group of cards being engaged against movement along the guide element by means of a stop member formed from a length of strip spring metal bowed intermediate its ends and extending across the guide element and having a pair of laterally projecting ends frictionally engaging remote edges of said spaced parallel flanges.

This invention further contemplates the provision of a resilient stop member adapted to readily be mounted on or removed from the guide element of an index panel, the ends of the member being frictionally engaged to the spaced flanges of the guide element by the force exerted by the bowed medial portion of the member tending to draw the ends toward each other.

This invention further contemplates the provision of a stop member formed of resilient spring metal to provide an arcuate body portion having depending ears lying in planes converging toward the axis of curvature of the body portion.

This invention embodies other novel features, details of construction and arrangement of parts which are hereinafter set forth in the specification and claims and illustrated in the accompanying drawing, wherein:

Fig. 1 is a front elevational view illustrating a card index panel and card stop member embodying features of this invention.

Fig. 2 is an enlarged sectional view taken along the line 2—2 of Fig. 1.

Fig. 3 is a detail view showing the stop member removed from the index panel.

Fig. 4 is a detail view showing an index card.

Fig. 5 is a fragmentary sectional view taken along the line 5—5 of Fig. 1.

Referring now to the drawing for a better understanding of this invention, an index panel 6, formed of sheet metal, is provided with a pair of spaced parallel card carrier elements 7—7 adapted to slidably receive a group of conventional record cards 8 or the like formed with cut out tongues 9—9. Each carrier element 7 is spot welded or otherwise secured to the panel 6 and formed with inner and outer side flanges 11 and 12 spaced outwardly from and parallel to the face of the panel. In mounting a record card 8 upon the panel 6, the tongues 9—9 are flexed from the plane of the card for engagement

2

under the outer flanges 12—12 in a manner well known in this art.

To support a group of overlapping record cards 8 in fixed position upon the panel 6, a stop member 14 is 5 adjustably positioned upon the carrier elements 7—7 for abutting engagement with the lower edge of the adjacent record card, as illustrated in Fig. 1. The stop member 14 is shown as comprising a length of resilient strip metal, such as spring steel, having a bowed body portion 16 10 and a pair of inturned ears 17—17 at the ends thereof to straddle the carrier elements 7—7 and to frictionally engage the edges of the outer side flanges 12—12.

As illustrated in Figs. 2 and 3 in the drawing, the ears 17—17 converge from the body portion 16 toward the 15 panel 6 and are drawn into tight frictional engagement with the edges of the outer flanges 12—12 by the clamping force exerted by the body portion. In applying the stop member onto the outer flanges 12—12 of the carrier elements 7—7, the bowed medial portion of the stop member is manually pressed toward the face of the panel 20 to cause the ears 17—17 to move apart into clamping engagement with the remote edges of the outer flanges 12—12.

After the stop member has thus been positioned upon 25 the carrier elements, the resilient body portion 16 continues to exert a force tending to draw the ears 17—17 toward each other into tight engagement against their related flanges 12—12. It will be noted that the ears 17—17 converge toward the panel 6 with their inner ends 30 spaced apart a distance slightly less than the distance between the remote edges of the flanges 12—12 to prevent accidental displacement of the stop member from the panel. To remove the stop member from the panel, either the upper or lower edge of the body portion 16 is 35 lifted away from the panel to pivot the member about its opposite edge and thus moving the inner edges of the ears 17—17 apart and into abutting engagement with the remote edges of the flanges 12—12, as illustrated in Fig. 5, after which the member may be lifted from the panel.

While this invention has been shown in but one form, it is obvious to those skilled in the art that it is not so limited but is susceptible of various changes and modifications without departing from the spirit and scope of the claimed invention.

45 I claim as my invention:

1. The combination with a record panel having spaced parallel coplanar guide flanges extending along and spaced from one face thereof to engage cut-out tongues of record cards, of a stop member formed from a length of thin strip resilient material comprising a body portion normally arched throughout its length, flat ears at the ends thereof, said ears converging from the body portion toward the face of the panel in line clamping engagement against their respective flanges, the end portions of said body portion engaging said flanges whereby the stop member may be manually rotated about one of its side edges toward one end of the panel to disengage the ears from said flanges, said body portion being manually flexed from its normally arched shape to a flat shape with the ears disposed substantially normal thereto during mounting of the stop member on said flanges.

2. In combination, a record panel having spaced parallel coplanar guide flanges spaced from one face of the panel to define therewith oppositely facing grooves to receive 65 cut-out tongues of record cards, and a resilient stop member of thin strip resilient material comprising flat ears at opposite ends of a body portion, the body portion being normally arched throughout its length with its end portions engaging said flanges, and the ears converging from the body portion toward the panel in clamping engagement with remote edges of said flanges, the length of said

body portion in a flattened condition being substantially equal to the distance between remote edges of said flanges, each of said ears being disposed at an acute angle of less than 10° to a plane extending vertically longitudinally centrally of the panel, whereby the body portion may be manually rotated about one of its side edges toward one end of the panel to cause the flanges to spread the free ends of the ears apart to disengage the stop member from the flanges, said body portion being manually flexed from its normally arched shape to a flat shape with the ears

disposed substantially normal thereto during mounting of the stop member on said flanges.
